US0D1000319S

(12) **United States Design Patent** (10) **Patent No.:** **US D1,000,319 S**
(45) **Date of Patent:** **** Oct. 3, 2023**

(54) **VEHICLE ROOF**

(71) Applicant: **Man Truck & Bus SE**, Munich (DE)

(72) Inventor: **Rudolf Kupitza**, Munich (DE)

(73) Assignee: **MAN TRUCK & BUS SE**, Munich (DE)

(**) Term: **15 Years**

(21) Appl. No.: **29/807,524**

(22) Filed: **Sep. 13, 2021**

Related U.S. Application Data

(62) Division of application No. 35/509,887, filed on Nov. 26, 2019 (U.S. filing date under 35 U.S.C. 384), and having an international filing date of Nov. 26, 2019, now Pat. No. Des. 933,532.
